Houston Oil Field Material Company, Inc.,
Houston, Tex., a corporation of Delaware

Application May 23, 1941, Serial No. 394,784

8 Claims. (Cl. 166—12)

This invention relates to new and useful improvements in retractable packers.

One object of the invention is to provide an improved packer which is particularly adaptable to use as a cement retainer and which may be readily retrieved after being set within a well bore.

Another object of the invention is to provide an improved packer which is adapted to be set and released by relative longitudinal movement of the parts thereof.

An important object of the invention is to provide an improved packer which is adapted to be set in sealing position within a well bore against upward displacement and having means for equalizing the pressures above and below the same prior to release or unsetting thereof, whereby the packer may be effectively employed as a cement retainer and readily released and retrieved after setting of the cement.

A particular object of the invention is to provide an improved packer, of the character described, which may be repeatedly set and released within a well bore without removing the packer from the well bore so as to permit use of said packer at various depths.

A further object of the invention is to provide an improved packer which, after having been set, may be actuated to relieve the pressure therebelow and then released without moving the entire structure of said packer.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a vertical sectional view of a device constructed in accordance with the invention.

Figure 2 is a view similar to Figure 1, showing the device in its packed-off position.

Figure 3 is a vertical sectional view of a tail pipe which may be connected to the lower end of said device.

Figure 4 is a view, partly in section and partly in elevation, showing the device in its releasable position.

Figure 5 is a view, similar to Figure 4, showing the device in its released position.

Figure 6 is a horizontal, cross-sectional view taken on the line 6—6 of Figure 1.

Figure 7 is a horizontal, cross-sectional view taken on the line 7—7 of Figure 1.

Figure 8 is a horizontal, cross-sectional view taken on the line 8—8 of Figure 1.

Figure 9 is a horizontal, cross-sectional view taken on the line 9—9 of Figure 1.

Figure 10 is a horizontal, cross-sectional view taken on the line 10—10 of Figure 1, and

Figure 11 is a horizontal, cross-sectional view taken on the line 11—11 of Figure 2.

In the drawings, the numeral 10 designates a cement retainer; however, it is pointed out that this device could be employed as a packer and is not limited to mere use as a cement retainer. The device is provided with an elongate, cylindrical, hollow mandrel or body 11 which extends substantially throughout the device. The mandrel extends below the lowermost end of said device, and is provided with external screw threads 12 at its lower end so as to receive a cage 13. Confined between the lower end of the mandrel 11 and within the cage 13 is a ball valve 14 so as to allow fluid to flow downwardly through said mandrel, and prevent fluid from flowing upwardly therethrough.

A tubular member or sleeve 15 surrounds the upper portion of the mandrel 11 and is slideable thereon. The upper end of the mandrel 11 has its outer circumference enlarged so as to form a shoulder 16, and is provided with a plurality of ports 17 near its upper end. The sleeve 15 is provided with internal screw threads 18 at its upper end, and the bore of said sleeve is reduced to form a shoulder 19. The reduced bore of the sleeve 15 slidably engages the mandrel below the shoulder 19. The bore of the sleeve 15, below the shoulder 19, is provided with a plurality of annular recesses 20. Lying within said recesses are circular packing rings 21 which prevent the flow of fluid thereby.

A plurality of ports 22 are provided in the sleeve 15 below the packing rings 21. All of the ports 22 are constructed identically and the description of one is deemed sufficient. The bore of the inner portion of said port is reduced so as to form a shoulder 23, and the outer portion of said bore is provided with internal screw threads 24. Slidable within the bore of said port is a pin 25 which has an enlarged head 26 that abuts the shoulder 23 so as to limit the inward movement of the pin. The screw threads 24 of each port receive an externally screw-threaded nut 27 and a coiled or helical spring 28 is confined between the enlarged head 26 of the pin and the nut so as to constantly urge said pin inwardly. An annular recess 29 is formed in the external surface of the mandrel

11 and the pins 25 engage within the recess when the ports 22 are in horizontal alignment with said recess, thereby releasably locking the sleeve 15 and mandrel together in the position shown in Fig. 1. In this position, an internal, annular shoulder 30, formed in the bore of the sleeve below the ports 22 by reducing the diameter of said sleeve bore, abuts the shoulder 16 of the mandrel. Thus, downward movement of the mandrel relative to the sleeve beyond the aforesaid locked position is prevented.

20 A plurality of annular, upwardly-directed ratchet teeth 31 are formed on the external surface of the sleeve 15 and the lowermost tooth is disposed in substantially the same plane as the shoulder 30 of said sleeve. Below the teeth 31, the external diameter of the sleeve is reduced and provided with a clutch member 32 which has an external diameter slightly less than the internal diameter of said teeth. External screw-threads 33 are formed in the sleeve some distance below the clutch member and receive an internally screw-threaded collar or nut 34 having a plurality of longitudinal recesses formed in its external periphery, as is most clearly shown in Fig. 9. The external diameter of the sleeve is again reduced below the screw-threads 33 to provide an annular, downwardly-directed shoulder 35 and, below this shoulder, said sleeve has a slightly enlarged external diameter, an annular, tapered shoulder 36 being formed at the upper end of this enlarged portion. As shown by the numeral 37, the lower extremity of the sleeve terminates above or short of the lower end of the device.

35 An annular flange 38 is provided on the outer circumference of the sleeve 15, below the screw-threaded portion 18 thereof, and a clutch means 39 is provided on the underside of said flange. A plurality of ports 40 are provided in said sleeve below the clutch means 39 and above the shoulder 19 so as to permit the passage of fluid from the exterior to the interior thereof. A coupling 41 is provided on the upper end of said sleeve and has an axial bore 42 extending therethrough. The coupling 41 is provided with an inwardly-directed flange 43 which extends into the bore 42 to form a reduced opening 44 and the underside of the flange 43 forms a shoulder 45 which limits the travel of the mandrel 11, as will be hereinafter explained. A plurality of splines 42' are provided on the coupling within the upper end of its bore 42 above the flange 43, and above said splines the coupling is provided with internal screw threads which may be either left-hand or right-hand as desired. A suitable member (not shown) is screwed into said threads, and has splines which mate with the splines 42' so that the connecting member acts to rigidly connect the device to the tubing (not shown).

40 A ring valve 46 encircles the upper end of the mandrel 11 and rests upon the shoulder 19 of the sleeve 15. The valve 46 has a depending annular flange 47 on its bottom, and is provided with a plurality of packing rings 48 which prevent the passage of fluid between said valve and the mandrel 11, and between said valve and the inner bore of the sleeve 15. A coil spring 49 is confined between the lower end of the coupling 41 and the upper end of the valve 46. The spring 49 acts at all times to urge said valve downwardly so that the flange 47 abuts the shoulder 19 of the sleeve 15 as long as the spring-pressure overbalances any opposing pressure. When the valve 46 is in the position as shown in Figure 1, fluid

5 cannot enter the ports 40 and pass upwardly through the sleeve into the coupling 41. It is pointed out that the device is run into the well on a suitable string of tubing or pipe (not shown).

10 As the pressure beneath the valve 46 is increased, it will urge the valve 46 upwardly against the tension of the spring 49 to such a point that fluid is free to flow from the ports 40 of the sleeve 15 through the ports 17 of the mandrel 11, and up through the coupling 41 and pipe (not shown).

15 A tubular member or collar 50 is disposed concentrically around the sleeve below the flange 38, and a clutch means 51 is provided on the upper end of said member for coacting with the clutch means 29 of said flange. A plurality of recesses 52 are provided in the outer circumference of said member below the clutch means 51. Dogs 53 lie within said recesses and are confined therein by screws 54. A plurality of recesses 55 are provided on the underside of the dogs 53, and confined within said recesses and the bottom of the recesses 52 are coil springs 56 which urge the dogs outwardly. It is pointed out that the dogs are free to move inwardly, compressing the springs 56, and their outward travel is limited by the screws 54.

20 The outer circumference of the member 50, below the lowermost screw 54 is reduced to form an annular depression 57 in the circumference of said member. A plurality of openings 58 are provided in the member 50 opening outwardly into the depression 57, and lying within said openings are nut sections 59 of a sectional nut, having ratchet teeth 60 on their inner surface. The teeth 60 mate with the teeth 31 of the sleeve 15. The outer portion of each nut section 59 is enlarged to form a shoulder 61 which abuts a shoulder 62 provided in the opening 58, thereby limiting the inward travel of said nut section. A plurality of garter springs 63 are disposed within the depression 57 and extend through openings in the nut sections 59 so as to constantly urge said nut sections inwardly as shown in Figure 1. 25 Due to the provision of the ratchet teeth 31 and 60, the nut sections will snap or be forced outwardly upon downward movement of the sleeve 15 relative to the member 50. Thus, mere lowering of the sleeve will cause the teeth 31 thereof to become disengaged from the teeth of the nut sections. However, in order to move the sleeve upwardly relative to the member, said sleeve must be rotated so as to screw the teeth together and then past each other.

30 35 A plurality of longitudinal openings or slots 64 are formed in the member 50 below the depression 57 and anchoring means, such as a double-step slip 65 having upwardly-directed, pipe-engaging teeth 66 on its outer surface, is positioned within each slot. The reverse or inner surface of each slip is tapered inwardly and downwardly toward the teeth 66 from its upper end as shown at 67 and then projects radially away from said teeth to provide an upwardly facing shoulder 68. A similar tapered surface 69 is provided below the shoulder 68, whereby each slip has a pair of similarly tapered surfaces instead of the usual single or continuous inclined inner surface. Each slip 65 is confined 40 within its slot 64 by a counter-sunk screw 70 which engages in the member 50 intermediate said slot and the depression 57 so that its head overlies the upper extremity of said slip. An upstanding, angular lip or flange 71 is formed 45 at the lower end of each slot so as to overlie

the lower extremity of the slip and assist in confining the same within said slot. Each screw 70 and lip 71 are so positioned relative to their respective slip that limited radial movement of said slip is permitted. It is pointed out that the number of slips is not critical and that the same could be provided with a different type of taper, such as the ordinary inclined surface with a tongue and groove arrangement.

A packing assembly is disposed below the member 50 and includes a cylindrical shoe or supporting element 12 which encircles the lower portion of the sleeve 15 and has an axial bore 73 extending therethrough. The upper portion of the bore is enlarged to form an upset shoulder 74 and provide an upstanding, axial collar 75 having its upper end internally screw-threaded. The shoe 12, below the shoulder 74, slidably engages the lowermost end portion of the sleeve 15. The lowermost end portion of the shoe 12 is provided with external screw threads 76. Above the screw-threaded portion, the outer circumference of said shoe is enlarged so as to form a flange 77. Surrounding the shoe and resting on said flange, are a plurality of packing rings 78. It is pointed out that any suitable compressible packer or packing rings may be employed.

Below the flange 77, and above the screw-threaded portion 76, the shoe 12 is provided with a plurality of upwardly-directed ports 79 which communicate with an internal, annular groove 80 provided in the bore of said shoe. Above the groove 80, the bore 73 is provided with a plurality of annular recesses 81 which receive packing rings 82. The packing rings 82 prevent the flow of fluid in either direction. Similar annular recesses 83 for receiving packing rings 84 are formed below the groove 80, whereby fluid is prevented from flowing upwardly or downwardly when the device is in the position shown in Figure 1.

The lowermost end of the shoe 12 is provided with a plurality of upwardly-extending slots 85, and latches 86 are pivotally suspended by pins 87 within said slots. A spring 88 encircles each pin 87 and acts to urge the latch suspended therefrom inwardly at all times. The mandrel 11 is provided with an annular groove 89 on its outer circumference, and the latches 86 engage within said groove when the device is in the position shown in Figure 1, and remain there engaged until the device is desired to be released, as will be hereinafter explained.

A cage 90, having an upstanding collar 91 which is internally screw-threaded, is attached to the screw-threads 76 of the shoe and the springs 88 bear against the inner surface of the collar. The lower end of the cage 90 slidably engages the mandrel 11 and is provided with a plurality of annular recesses 92 for receiving packing rings 93, the rings sealing the space between said cage and mandrel and being so constructed that the upward flow of fluid through said space is prevented. However, the downward flow of fluid is permitted by the construction of the packing rings.

A flanged bushing 94 is screw-threadedly attached to the upper end of the shoe collar 75 and slidably engages the intermediate portion of the sleeve 15 so as to be disposed above the nut 34 carried by the screw-threads 33 of said sleeve. The lower end of the bushing 94 is adapted to engage the upper end of the nut to support the shoe 12 and suspend the same from the sleeve. Clutch means 94' is provided at the upper end of 75

the bushing for coaction with the clutch means 32 of the sleeve upon downward relative movement of said sleeve. A plurality of elongated, longitudinal grooves 95 are formed in the exterior of the collar 75 immediately below its connection with the bushing 94. Actuating means, such as an elongated ring or slip expander 96 is disposed, in sliding engagement with the exteriors of the collar and bushing above the packing rings 78 and has its upper portion engaging within the enlarged lower portion of the member 50. The outer surface of the ring 96 is provided with a pair of similarly tapered surfaces 97 which are complementary to the tapered surfaces 98 of the slip 65. Due to the tapered surfaces of the ring and slip, upward movement of the ring relative to said slip will expand or move the slip outwardly in a radial direction.

The ring 96 is provided with a plurality of screw-threaded openings 98, each of which receives a pin 99 having an inwardly-directed lug 100 for engaging within one of the grooves 95 of the collar 75. For establishing communication between the interior of the collar 75 and the grooves 95, a plurality of ports 101 are formed in said collar. Similar ports 102 are formed in the ring adjacent its lower end and in registration with the grooves so that communication between said grooves and the exterior of said ring is established. Thus, fluid may flow from the exterior of the ring, through said ring and then through the collar 75, but is prevented from flowing downwardly by the packings 82 and 84.

In the operation, the tool is suspended from a suitable tubular member by the collar 41, and is run into the hole or well bore until the position has been reached at which it is desired to set said device. It is pointed out that the dogs 53 are being urged outwardly at all times by the springs 56 so that they slidably engage the pipe or casing, and also said dogs are free to move inwardly if necessary.

It is pointed out that sometimes while the device is being run into the well, the teeth 31 may snap through the nut sections 59. However, when the position in which the device is desired to be set has been reached, the sleeve 15 may be rotated while the member 50, ring 96 and shoe 12 will be held from rotating by the dogs 53. Upon right-hand rotation, or left-hand, if desired, the teeth 31 are screwed upwardly through the nut sections 59 (Fig. 2). Even though the teeth were completely below said nut sections, the sleeve 15 may be raised until the teeth 31 contacted the teeth 60 of the nut sections 59 and then rotated so as to pass therethrough. An upward pull is then exerted upon the sleeve so as to move the nut 34 under the bushing 75 and exert an upward pull on the shoe 12. This will usually occur while the threads 31 are passing through the nut sections 59 so that the ring 96 is being moved under the slips 65, and continued upward movement of the sleeve 15 will expand said slips and expand the packer so that the tool will be in the position shown in Figure 2. At this time the tool is set and is ready for use.

In employing the device as a cement retainer, the cement is pumped down through the tubing (not shown) through the collar 41 and down through the mandrel 11, unseating the ball 14 so as to allow the cement to flow out through the cage 13. In using this device as a cement retainer, there is usually provided above the device a suitable set of jars which will allow fluid, when said jars are open, to flow down the tubing or

by pumping down the tubing will act through said jars. Such a suitable set of jars is shown in the patent to Ross Bassinger, No. 2,317,021, granted April 20, 1943, for By-pass and releasing means. In cementing practice there is usually mud or what is commonly called drilling fluid in the tubing, and it is desirable to pump this out into the casing above the packer. This is done after the packer has been set, and then the drilling fluid is followed by a clear water which is followed by cement. The jars should be shut before the cement reaches the predetermined point. The jars are ordinarily operated by longitudinal movement, and to open them the tubing is slightly lowered. When this occurs the upward strain on the device is relieved. However, pressure beneath the packer will keep the device set, but it is desirable to have some means of locking the sleeve 15 from a downward movement. This is done by means of the pins 29 and the annular recess 24 in the mandrel 11, which locks the mandrel and the sleeve together. The mandrel 11 cannot move downwardly as it is suspended by the latches 86, and a pressure is acting upwardly on the lower end of the mandrel as well as the lower end of the packer, thereby supporting the sleeve 15 and the coupling 41 and other means between it and the lower end of the jars.

After the desired amount of cement has been placed in the well, the pump pressure down through the tubing and the structure is shut off. The pressure of the well beneath the packer will act to move the ball 14 up against the lowermost end of the mandrel 11 so as to prevent back flow of the cement. At this time it is desirable to wash the cement out of the tubing above the structure. To accomplish this, the pump pressure and fluid is started down through the casing so that the fluid under pressure will flow downwardly around the tubing and into the ports 40 of the sleeve 15. The pressure will act on the underside of the ring valve 46, moving it upwardly so as to allow the fluid to flow from the ports 40 through the ports 17 and then past the upper end of the mandrel 11.

It is pointed out that in the usual practice, the well is full of fluid when the device is run into the well, and the mud stream is directed into the casing instead of down through the tubing as is commonly done in drilling. After the tubing has been washed, the pump pressure is again shut off and the device remains in this position until the cement has had sufficient time to harden. It is then desirable to release the structure. The cage 13 at the lowermost end of the mandrel 11 will be abutting the cement or may be slightly submerged therein; and due to the fact that there is fluid in the well at the time the device is set and the cement is inserted, there will be fluid between the top of the cement and the underside of the packing 18, so that said pressure must be disposed of, or relieved before any portion of the device may be moved downwardly. Obviously, the mandrel 11 cannot be moved downwardly as it is abutting the cement.

To relieve this pressure, the tubing (not shown) is lowered, the teeth 31 on the sleeve 15 snap through the nut sections 59, and as the sleeve is moved downwardly, due to the reduced portion below the nut 34, pressure below the packer may flow through said reduced portion up through the openings in the nut 34, and out through the ports 101 and 102 as shown in Figure 4. This pressure flows through the opening 19 and the annular groove 80 so that the pressure on either

side of the packer is equalized. While the pressure is being equalized on either side of the packer, the lower end 37 of the sleeve 15 will be abutting or in contact with the latches 86, moving them outwardly from the mandrel thereby removing their innermost end from the annular recess 89 and unlocking the shoe 72 from said mandrel, thus allowing the shoe to move downwardly. The latches 86, engaging within the groove 88, prevent the mandrel 11 from being pumped upwardly when the cement is being pumped therethrough.

In order to pump the cement down through the structure and unseat the ball valve 14, the pump pressure must be greater than the well pressure beneath said ball valve. The pump pressure while acting upon the cement, will also act upon the lower end of the mandrel, and, if the latches 86 were not employed, the mandrel might be pumped up the device so that the uppermost end would strike the shoulder 45 of the coupling 41. However, the latches 86 prevent this from occurring. By continued downward movement of the sleeve, the nut 34 strikes the shoulder 74 of the shoe 12 and the relief of the pressure will allow the packing to resume its original position; and, by the nut striking the shoulder 74, the taper of the ring 96 is pulled out from under said slips so as to retract the same (Fig. 5). The device is now in its released position, and it is only necessary to pull upwardly to retrieve the entire structure. The teeth 31 will not pass through the nut sections 59, and therefore the device cannot be set.

It is pointed out that the pins 25 of the sleeve 15 are normally engaging within the recess 29 of the mandrel 11 which locks the sleeve and the mandrel together so that movement of the sleeve also moves the mandrel. However, when the tool is desired to be released, it is necessary to snap the pins out of said recess. Thus, the sleeve may move downwardly relative to the mandrel. The pins are for the purpose of locking the sleeve and the mandrel together while the tool is being set.

In some instances the tool cannot be retrieved due to some condition, such as leaking cement or the like, and it is desirable to release the tubing from said device. If the tool is in the position shown in Figure 2, the clutch means 39 and 51 cannot be engaged due to the fact that the sleeve 15 cannot be moved downwardly far enough for this to occur. However, the clutch 32 of the sleeve 15 and the clutch 94' of the bushing 94 may be engaged due to the fact that said sleeve may be lowered relative to the shoe 72 until its lower end strikes the latch 86. Thus said sleeve is held from rotating by the engagement of the clutches, and if desired left-hand threads may be provided at the upper end of the collar 41, and the tubing released from the device by right-hand rotation. However, right-hand threads could be used.

The clutch means 39 and 51 may be employed when the clutches 94' and 32 are not engaged so that the operator may at all times release his tubing from the device. Thus with this structure, the device is released by equalizing the pressure below the packer and above the packer.

It is pointed out that after the device has been released and it is desirable to move the device down farther, if cement has not been used, or it is desirable to set the device at some point above the cementing operation, this may be accomplished by rotating the suspending pipe, which will rotate the sleeve 15 and allow the threads or teeth 31 thereof to pass through the nut sections

59. The device will then resume its original position as shown in Figure 1.

Thus this device enables the operator to set and release this device as many times as desired, and allows him to cement with the structure and hold the pressure on said cement until it has hardened to prevent the cement from blowing back up the well after the packer has been removed. After the cement has hardened, the operator may equalize the pressure on either side of the packer, allowing the packing to resume its original position and enabling the device to be retrieved.

After the device has been released from its set position, the mandrel may be slightly moved up within the device. However, the weight of said mandrel will automatically move it downwardly so that the latches 86 and the spring pins 25 may again engage within their respective recesses. However, to insure this movement of the mandrel downwardly, a spring (not shown) may be employed and confined between the upper end of the cage 13 and the lower end of the cage 90, thereby insuring that said mandrel will be pulled downwardly so that it will resume its original position as shown in Figure 1.

The hollow mandrel or body 11 may be referred to as a conductor. The ring valve 46, and the ports 17 and 40 constitute fluid-pressure responsive means for establishing inward flow of a washing fluid. The packing assembly, as illustrated, includes primarily the elements 72, 75, 78 and 96, while the element 50 forms a part of the means for supporting the casing engaging slips 65. The element 50 may also be considered as constituting a support for the clutch means 68, which is adapted to engage with the upwardly directed teeth 31 carried by the tubular member 15. The elements 86, 89 and 90 constitute means for detachably connecting the packing assembly with the conductor 11. The elements 79 and 80, and 101 and 102 provide passages respectively below and above the packers 78, while the reduced portion 73 and recesses in the nut 34 form a by-pass between these passages; however, all of these elements may be referred to as a by-pass. The elements 50, 53 and 65 may be referred to as anchoring means.

Various changes, alterations and modifications may be made in the size, shape and arrangement of the herein described elements, within the scope of the appended claims.

What we claim and desire to secure by Letters Patent is:

1. A device of the character described including, a support, a sleeve depending from said support, a packing assembly including a packer surrounding said sleeve, means connecting said packing assembly with the sleeve for limited sliding movement thereon, anchoring means surrounding said sleeve and engageable by the packing assembly for setting the anchoring means and thereby the packer when the sleeve is moved in an upward direction relative to the packing assembly, a conductor slidably mounted within the sleeve, cooperating means carried by the sleeve and conductor to prevent relative sliding movement therebetween in one direction while permit-

ting such movement therebetween in the opposite direction, and means for detachably connecting the packing assembly and conductor together to prevent upward movement of the latter, said last-named means being operable by the sleeve to disconnect the packing assembly from the conductor when the sleeve is moved in a downward direction relative to the conductor to thereby release the packer.

2. A device in accordance with claim 1, wherein there is a back pressure valve carried by the conductor for closing off upward flow of fluid therethrough.

3. A device in accordance with claim 1, wherein there is a fluid by-pass passage through the sleeve and conductor, and a pressure actuated valve normally biased to a position to prevent passage of fluid through said by-pass passage and operable to permit inward flow.

4. A device in accordance with claim 1, wherein there is a fluid by-pass passage around the packing assembly and formed in the latter and the sleeve, said passage being normally closed when the packer is set and being opened to permit the passage of fluid therethrough so as to equalize the fluid pressure on both sides of the packer when the sleeve is moved in a downward direction relative to the conductor to disconnect the packing assembly from the conductor and to thereafter release the packer.

5. A device in accordance with claim 1, wherein the means for detachably connecting the packing assembly and conductor include arms having one of their ends pivoted to the packing assembly and extending below said sleeve and across the path of downward movement of the sleeve relative to the conductor and having their opposite free ends seating within an external circumferential groove formed in the conductor.

6. A device in accordance with claim 1, wherein there are cooperating means provided on the sleeve and on the anchoring means detachably engageable for supporting the anchoring means in retracted position with respect to the casing wall and the packing assembly.

7. A device in accordance with claim 1, wherein there are cooperating clutch means provided on the sleeve and on the anchoring means operable when engaged to hold the sleeve against rotation so as to permit the support to be released from the sleeve.

8. A device of the character described including, a sleeve member, a packing assembly surrounding the sleeve member and movable with respect thereto, anchoring means carried by the sleeve member, means carried by the anchoring means frictionally engaging a well casing, means carried by the packing assembly for actuating the anchoring means, annular projections on the sleeve, and spring-pressed nuts carried by the anchoring means having recesses receiving the projections of the sleeve and movable to permit the projections to move longitudinally thereof when the sleeve is moved in one direction.

GEORGE E. JUSTICE.
FRANK M. THURSTON.
